UNITED STATES PATENT OFFICE.

SUSAN S. FRACKELTON, OF MILWAUKEE, WISCONSIN.

CHINA-FIRING APPARATUS.

SPECIFICATION forming part of Letters Patent No. 349,935, dated September 28, 1886.

Application filed June 1, 1886. Serial No. 203,735. (No model.)

To all whom it may concern:

Be it known that I, SUSAN S. FRACKELTON, of Milwaukee, in the county of Milwaukee and in the State of Wisconsin, have invented certain new and useful Improvements in China-Firing Apparatus; and I do hereby declare that the following is a full, clear, and exact description thereof.

My invention relates to an apparatus for firing decorated china, and has for its objects to obtain the best possible results in that art with the least outlay of time, labor, and expense.

A further object of my invention is to provide a china-firing apparatus that may be successfully and economically employed by individuals other than specialists in the peculiar art to which it pertains.

My invention, therefore, consists in certain peculiarities of construction and arrangement of parts, as will be hereinafter described with reference to the accompanying drawing, in which is represented a sectional view of my apparatus.

Referring by letter to the drawing, A represents a ring of suitable dimensions integral with or connected to legs B, thus forming a stand for the support of my china-firing apparatus.

Designed to rest within the ring A is the body portion C of an outer shell that has a removable top, C', both these parts being preferably composed of cast metal and provided with a lining, D, of fire-clay or other suitable refractory material, said material being trued by a mold, so as to have a uniform thickness throughout said shell. The lower part of the shell-body C is preferably cup-shaped and provided with an opening of suitable dimensions in its bottom.

Vertically extended in an upward direction from the sides of the bottom opening in the shell-body C is a continuous flange, b, and extended from the upper edge of this shell-body is a continuous horizontal flange, c, that is equal in width to the vertical one, b, these flanges serving to determine the thickness and confine the lining D of this shell-body, said lining being applied in a plastic state. The removable top C' of the shell is preferably

dome-shaped and provided with continuous vertical and horizontal flanges d e, the one d being upwardly-extended to form a flue, F, and the one e designed to rest upon the corresponding one, c, of the body portion C of said shell. The dome-shaped top C' is also provided with an opening, f, from the edges of which is inwardly extended a continuous conical flange, g, having a width equal to the ones d e, and these several flanges serve the same purpose as the ones b c in the body portion C of the shell. The lower outer edge of the top C' is provided with a bead, h, that is vertically depended for about one-half its width, and has the inner face of this depending portion in conformity to the body portion C of the shell, so as to come over around the latter to form a tight joint when the two parts are united, this construction serving to retain the heat in said shell.

The opening in the bottom of the shell-body is designed to fit snugly over the burner of a gas-stove, G, or other suitable heat-generating apparatus, so as to exclude the outside air at this point, sufficient air being drawn up through the heating apparatus to insure thorough combustion. The flue F, that forms part of the dome-shaped top C', is connected with an escape-pipe, H, that carries off the smoke and other products of combustion from the heat-generating apparatus, said pipe being provided with the usual damper, I. The body portion C of the shell is internally provided with lugs i, that extend through the refractory lining D, and are cut away to form seats for lugs k upon the exterior body part K of a china-containing receptacle, the latter being preferably composed of cast metal, and provided with a removable dome-shaped cover, L, that has a bead, m, around its lower edge similar to the one h on the top C' of the shell-body C, and this bead m fits around upon an annular shoulder, n, at the top of said part K, to form a tight joint, this construction serving to exclude the products of combustion from and retain the heat in said receptacle.

The cover L of the receptacle K is provided with a hollow conical extension, p, that passes through the opening f of the shell-top C', this extension serving as a peep-hole through

which to observe the contents of said receptacle during the process of firing.

Seated in the lower part of the receptacle K is a removable perforated plate, M, of any suitable dimensions, this plate serving to support small articles of china to be fired, and the space *r* below said plate may also be utilized for containing a small article or articles of such ware.

10 At any desirable point upon the interior of the receptacle K are located lugs *s*, that serve to support miniature grates N, on which are placed the larger pieces of china to be fired.

The diameter of the respective parts comprising the outer shell is considerably greater than that of the corresponding parts of the china-containing receptacle, and thus an air-space, *t*, is formed that entirely surrounds said receptacle. It will be noticed that the air-

15 space *t* has its greatest area between the lower ends of the parts C K, to insure thorough combustion at this point, and that the end *u* of said part K extends down into the flame from the heat-generating apparatus G, this latter

20 serving to cause an equal diffusion of heat, for the reason that the lining D is of equal thickness throughout, while the china-receptacle is hung so that its vertical center is in line with that of the shell, and the flame being

25 equally divided by the end *u* prior to its entrance into the air-space, is caused to uniformly ascend up around all sides of said receptacle, the latter being substantially of conical form, as is also the interior of the shell. The

30 bead *m* on the cover L projects into the air-space and serves to retard the heat, and thereby prevent its too rapid escape with the other products of combustion through the flue F, and it has been found in practice that, by the pec-

35 culiar construction and arrangement of parts above described, said heat is uniform throughout the entire apparatus, thereby insuring the perfect firing of china regardless of its location in the inner receptacle, as frequently in 40 charging said receptacle the china comes above the top of the body part K to such a height as to fill the space formed by the dome-shaped cover L.

When the apparatus is first fired, the peephole *p* is left open to allow the escape of steam generated from the moisture in the material composing the articles to be burned, and the pigments that are employed thereon for decorative purposes, and after this steam has ceased 50 to escape, said hole is plugged up to retain the heat, the latter being usually increased at this time.

The apparatus being extremely simple in construction, can be manufactured at comparatively small cost, of various sizes, and as ordinarily constructed is designed to be portable, so as the same can be readily set away when not in use.

A further advantage of my invention lies in 60 the fact that it not only does away with the dirt and care incident to the ordinary devices

for firing china, but at the same time dispenses with the services of a professional fireman, thereby reducing the cost of this class of work to a minimum, and securing the best possible 70 results attainable in the art.

Having thus fully described my invention, what I claim as new, and desire to secure by Letters Patent, is—

1. In a china-firing apparatus, the combination of a suitably suspended heat-refracting shell having an opening in its top and bottom, respectively, an inner receptacle for the china having a less diameter throughout than the interior of the shell, whereby a continuous air-space is left between said parts, and a detachable heat-generating apparatus having a tight connection with the bottom opening in the shell, substantially as and for the purpose set forth. 75

2. In a china-firing apparatus, the combination of a suitably-suspended outer shell having its body portion and removable top composed of cast metal lined with fire-clay or other heat-refracting material, the former part having an inlet and the latter an outlet opening, a cast-metal receptacle for china suspended within the shell and having a less diameter throughout than the interior of said shell, whereby a continuous air-space is left between the parts, 90 and a heat-generating apparatus having a tight connection with the inlet at the bottom of the shell-body, substantially as and for the purpose set forth. 95

3. In a china-firing apparatus, the combination of a suitably-suspended outer shell having its body portion and removable top composed of cast metal, the former part having a vertical upwardly-extended flanged opening in its bottom, and a horizontal inwardly-extended 100 flange at its upper edge, and the top part provided with a central vertical flue extended down inside to form a flange, and the lower edge of this part inwardly extended to form a horizontal flange corresponding to the one on 105 said former part, a lining of heat-refracting material held between and of a thickness equal to the width of the several flanges, a receptacle for china suspended within the shell, and having a less diameter throughout than the interior of said shell, and a heat-generating apparatus having a tight connection with the inlet at the bottom of the shell-body, substantially as and for the purpose set forth. 110

4. In a china-firing apparatus, the combination of a suitably-suspended heat-refracting shell having an opening in its top and bottom, respectively, and said top provided at its lower edge with a vertically-dependant flange that comes over around the upper part 120 of the body portion, a sectional cast-metal receptacle for the china suspended within the shell and of a less diameter throughout than the interior of the latter, and the top section of this receptacle provided with a bead around 125 its lower edge that partially obstructs the space between said receptacle and shell, and 130

a heat-generating apparatus having a tight connection with the bottom opening in the shell, substantially as and for the purpose set forth.

5. In a china-firing apparatus, the combination of a suitably-suspended heat-refracting shell having an opening in its top and bottom, respectively, an inner receptacle for the china that terminates in a point at its bottom and is 10 of less diameter throughout than the interior of the shell to leave a continuous air-space that has its greatest area between the lower ends of said parts, and a detachable heat-generating apparatus having a tight connection 15 with the bottom opening of the shell, substantially as set forth.

6. In a china-firing apparatus, the combination of a suitably-suspended heat-refracting shell of substantially conical form upon its interior, and provided with a top and bottom opening, an inner receptacle for the china of a form similar to that of the interior of said shell but of less diameter throughout, whereby a continuous air-space is left between said 25 parts, and a detachable heat-generating apparatus having a tight connection with the bottom opening of the shell, as and for the purpose set forth.

7. In a china-firing apparatus, the combination of a suspended sectional cast-metal shell having a lining of refractory material, an opening in its top and bottom and lugs that project through the lining, a sectional cast-metal receptacle having lugs upon its body 35 portion that rest upon the lugs of the shell and is of less diameter throughout than the interior of the latter, whereby an air-space is formed between said parts, the top section of this receptacle provided with a hollow conical

extension extended through a corresponding opening in the top of the shell, and its body portion internally provided with lugs and removable grates supported by said lugs, and a heat-generating apparatus having a tight connection with the bottom opening of the shell, 45 substantially as and for the purpose set forth.

8. In a china-firing apparatus, the combination of a sectional heat-refracting shell having a cup-shaped bottom and dome-shaped top, each provided with a vertical opening, and 50 the interior body portion of this shell provided with a series of lugs, a cast-metal sectional receptacle for the china similar in contour to the former part but of less diameter throughout than the interior thereof, the body 55 portion of this receptacle provided, upon its exterior with a series of lugs that rest on those of the shell and upon its interior with another series of lugs, grates supported upon these latter lugs and a removable perforated plate, 60 and the top section of said receptacle provided with a projecting bead or flange around its lower edge and a conical hollow extension that passes through a corresponding opening in the shell top, a heat-generating apparatus 65 having a tight connection with the bottom opening in the shell, and a supporting-frame comprising an open seat for said shell, and suitable legs secured at their upper ends to the seat, substantially as set forth. 70

In testimony that I claim the foregoing I have hereunto set my hand, at Milwaukee, in the county of Milwaukee and State of Wisconsin, in the presence of two witnesses.
